UNITED STATES PATENT OFFICE.

CHARLES A. PRATT, OF CHICAGO, ILLINOIS, ASSIGNOR TO GOODMAN MANUFACTURING COMPANY, OF CHICAGO, ILLINOIS, A CORPORATION OF ILLINOIS.

CUTTER-ARM FOR MINING-MACHINES.

1,322,819.

Specification of Letters Patent. Patented Nov. 25, 1919.

Application filed January 22, 1916. Serial No. 73,567.

To all whom it may concern:

Be it known that I, CHARLES A. PRATT, a citizen of the United States, residing at Chicago, in the county of Cook and State 5 of Illinois, have invented a certain new and useful Improvement in Cutter-Arms for Mining-Machines, of which the following is a specification.

This invention relates to improvements 10 in cutter arms for mining machines, and has for its object to provide a new and improved device of this description.

The invention is illustrated in the accompanying drawings, wherein—

15 Figure 1 is a plan view of a cutter arm embodying the invention, with parts omitted;

Fig. 2 is a sectional view taken on line 2—2 of Fig. 1.

20 Fig. 3 is a plan view showing the entire cutter arm.

Like numerals refer to like parts throughout the several figures.

The cutter arm is made up of a suitable 25 frame-work about which the cutter chain passes, the cutter chain sliding in a guiding groove on the cutter arm. The frame of the cutter arm is made up of two side members 1, each having an enlargement or 30 a thickened portion 4 at one side, and a thinner portion 8 connected therewith. In the construction shown, the side members are I-shaped in cross section, and I prefer to use as these side members rolled beams, such 35 for example, as ordinary railway rails. When this construction is used, the enlargement 4 forms one flange of the rail, preferably the head thereof, while the thinner portion 8 forms the web, the base forming the

40 flange 2. The bases or flanges 2 of these side members are opposed to each other and are separated by a space 3. Connected with the outer flange 4 of each side member are the two guiding members 5. These members are 45 preferably rolled members and are provided at their outer edges with the flat projecting faces 6 engaged by the chain and the depressed face 6 which engages the flange of the side member, there being a space between 50 said flange and the faces 6 which form grooves for guiding parts on the cutter chain. The guiding members 5 are fastened to the flange 4 in any desired manner, as by the fastening devices 5^a. These guiding 55 members have projecting parts 7, which en-

gage the side members 1 between the two flanges. I prefer to make the projecting parts 7 curved. The web 8 of each side member is preferably provided with grooves 9 on the opposite sides thereof, into which 60 the projecting parts 7 fit.

In the operation of the device, the chain exerts a pressure on the faces 6—6, tending to separate said faces, and in many instances this pressure at times becomes so great as 65 to make it difficult to hold the guiding members in place and in proper relation to each other. By means of the present construction this difficulty is obviated as the fulcrum of each guiding member is located at the 70 point where the projection 7 engages the web 8 and hence the lever arms are thus so arranged as to permit the construction to resist the pressures without the guiding members being spread apart. It is very essen- 75 tional, for the proper operation of the chain, that the distance between the faces 6 be maintained at all times, and I have found that by means of the present construction this result is attained.

In making up the device, where the side members are railway rails, in order to secure the proper accuracy as to the distance between the faces 6 and 6, I prefer to plane off the faces 10 of the ball of the rail, the 80 face 10 on one side and the groove 9 on that side being planed simultaneously so as to insure accuracy.

I have described in detail a particular construction embodying the invention, but 90 it is of course evident that the parts may be varied in certain particulars without departing from the spirit of my invention, and I therefore do not limit myself to the particular construction shown.

I claim:

1. A cutter arm for mining machines, comprising two side members, said side members having an I-shaped cross section, consisting of two separated flanges, two side chain-guiding members associated with each side member, said guiding members fastened to one of the flanges of the side member and having projecting portions which project outwardly to form a guiding groove for the chain, said guiding members also having rearwardly projecting portions which project beyond said flange and taking the strain when the chain is cutting, and a connection between 100 105 110

said rearwardly projecting portions and the web of the side member with which they are connected so that said web resists the movement of said projections due to pressure from the chain.

2. A cutter arm for mining machines, comprising two side members, each of said side members provided with flanges connected together by a web, two side guiding members connected to the outer flange of each side member on opposite sides thereof and projecting outwardly so as to form a guiding groove for the cutter chain, said guiding members having rearwardly projecting portions which project beyond the flange and engage the web of said side member.

3. A cutter arm for mining machines, comprising two side members, each of said side members provided with flanges connected together by a web, two side guiding members connected to the outer flange of each side member on opposite sides thereof and projecting outwardly so as to form a guiding groove for the cutter chain, said guiding members having rearwardly projecting portions which project beyond the flange and engage the web of said side member, the said web provided with grooves on opposite sides thereof into which said rearwardly projecting portions are received.

4. A cutter arm for mining machines, comprising two side members, each of said side members comprising a thin web portion and a thick outer portion connected together, two guiding members connected to the thick outer portion of each side member on opposite sides thereof and projecting outwardly so as to form a guiding groove for the cutter chain, said guiding members having rearwardly projecting portions which project inwardly beyond the thick portion and part way along the web portion, and a connection between the said rearwardly projecting portions of the guiding members and said web portion so that the web portion resists the movement of said rearwardly projecting portions of the guiding members due to pressure from the chain.

5. A cutter arm for mining machines, comprising two side members, each of said side members comprising a thin web portion and a thick outer portion connected together, two guiding members connected to the thick outer portion of each side member on opposite sides thereof and projecting outwardly so as to form a guiding groove for the cutter chain, said guiding members having rearwardly projecting portions which project inwardly beyond the thick portion and part way along the web portion, the said web portion provided with grooves, and the projecting portions of the guiding members

projecting into said grooves so that said web portion resists the movement thereof due to the pressure from the chain.

65

6. A cutter arm for mining machines, comprising two side members, each of said side members provided with flanges connected together by a web, two guiding members connected to the outer flange of each of said members on opposite sides thereof and projecting outwardly so as to form a guiding groove for the cutter chain, said guiding members having rearwardly projecting portions which project beyond the flange and part way along the web, said projecting portions bent inwardly toward each other and engaging said web so that the web resists the movement of the rearwardly projecting portions of said guiding members due to pressure of the chain tending to separate said guiding members.

75

7. A cutter arm for mining machines comprising two chain guides on opposite sides thereof, each guide comprising a thick portion, one side of which provides a backing for the chain, a thin portion connected with the other side of said thick portion, two guiding members secured to each thick portion on opposite sides thereof and projecting outwardly so as to form a guiding groove for the cutter chain, said guiding members having rearwardly projecting portions which project inwardly beyond said thick portion and part way along the thin portion, and a connection between the said rearwardly projecting portions and the thin portion so that the thin portion resists the movement of the said rearwardly projecting portions of the guiding members due to the pressure from the chain.

85

8. A chain guiding member for cutter arms for mining machines comprising two side members, each of said side members provided with separated flanges connected together by an intervening web, two guiding members connected to the outer flange of each side member on opposite sides thereof and projecting outwardly so as to form a guiding groove for the cutter chain, said guiding members having rearwardly projecting portions which project beyond the flanges, the ends of said rearwardly projecting portions engaging said web, a portion of said rearwardly projecting portions between said ends and said flange being free from said web.

90

In testimony whereof, I affix my signature in the presence of two witnesses this 7th day of January, 1916.

CHARLES A. PRATT.
